(57) CLAIM

The ornamental design for a case cover, as shown and described.

DESCRIPTION

FIG. 1 is a front view of case cover according to the present invention.

FIG. 2 is a rear view of the case cover of FIG. 1.

FIG. 3 is a top view of the case cover of FIG. 1.

FIG. 4 is a bottom view of the case cover of FIG. 1.

FIG. 5 is a right side view of the case cover of FIG. 1.

FIG. 6 is a left side view of the case cover of FIG. 1; and,

FIG. 7 is a perspective view of the case cover of FIG. 1. The broken lines of FIG. 7 are for illustrative purposes only and forms no part of the claimed design.
